CLAIM

An ornamental design for a merchandising display, as shown and described.

DESCRIPTION

FIG. 1 is a perspective view showing the front of a merchandising display embodying my new design;

FIG. 2 is a rear elevational view of the merchandising display of FIG. 1;

FIG. 3 is a perspective view showing the front, left and rear sides of the merchandising display of FIG. 1;

FIG. 4 is a perspective view showing the front, left and right sides of the merchandising display of FIG. 1;

FIG. 5 is a bottom plan view of the merchandising display of FIG. 1;

FIG. 6 is a bottom perspective view of the merchandising display of FIG. 1;

FIG. 7 is a top plan view of the merchandising display of FIG. 1;

FIG. 8 is a top perspective view of the merchandising display of FIG. 1;

FIG. 9 is a perspective view showing the front of a second alternate preferred embodiment of a merchandising display;

FIG. 10 is a rear elevational view showing the left and rear sides of the second alternate preferred embodiment of the merchandising display of FIG. 10;

FIG. 11 is a perspective view showing the front, left and right sides of the second alternate preferred embodiment of the merchandising display of FIG. 10;

FIG. 12 is a bottom perspective view of the second alternate preferred embodiment of the merchandising display of FIG. 10; and,

FIG. 13 is a top perspective view of the second alternate preferred embodiment of the merchandising display of FIG. 10.
